United States Patent

Des. 235,360
Patented June 10, 1975

235,360

BOWLING SCORER

Stephen F. Brucker, Dayton, Ohio, assignor to
AMF Incorporated

Filed Sept. 13, 1973, Ser. No. 396,880

Term of patent 14 years

Int. Cl. D21—02

U.S. Cl. D34—5 DD

FIG. 1

FIG. 2

FIG. 1 is a perspective view of a bowling scorer showing my new design; and

FIG. 2 is a rear perspective view thereof.

I claim:

The ornamental design for a bowling scorer, substantially as shown.
